UNITED STATES PATENT OFFICE.

JAMES R. MOFFATT, OF CHICAGO, ILLINOIS, ASSIGNOR TO UNION SPECIAL MACHINE COMPANY, OF CHICAGO, ILLINOIS, A CORPORATION OF ILLINOIS.

PRESSER FOOT.

Application filed September 1, 1921. Serial No. 497,563.

To all whom it may concern:

Be it known that I, JAMES R. MOFFATT, a citizen of the United States, residing at Chicago, in the county of Cook, State of Illinois, have invented certain new and useful Improvements in Presser Feet, of which the following is a description, reference being had to the accompanying drawing, and to the figures of reference marked thereon.

10 The invention relates to new and useful improvements in presser feet for sewing machines, and more particularly to a presser foot which is adapted to be used in connection with the forming of a flat covered seam.

15 An object of the invention is to provide a presser foot of the above type having a slot for guiding and overlapping the edge portions of the fabric sections, which presser foot is provided with a section in rear of the

20 needles which is rigidly supported by the shank of the presser foot, and wherein the presser foot sections at each side of and immediately in front of the needles are yieldingly supported by said shank.

25 A further object of the invention is to provide a presser foot of the above type wherein the tension of the spring on one or more of the yielding sections may be adjusted to vary the pressure of said section

30 against the fabric.

A still further object of the invention is to provide a presser foot of the above type wherein the slot for guiding and overlapping the edge portions of the fabric sections

35 is formed by the yieldingly supported sections of the presser foot so that said sections may shift relative to each other to permit the free passage of cross seams.

40 A still further object of the invention is to provide a presser foot of the above type wherein the rigidly supported section in rear of the needles is extended to one side of and above one of the yielding sections so as to support the stationary member of a trimming mechanism.

These and other objects will in part be obvious and will in part be hereinafter more fully disclosed.

In the drawings which show by way of illustration one embodiment of the invention:—

Figure 1 is a view partly in side elevation and partly in vertical section showing a portion of the sewing machine having my improvements embodied therein; 55

Fig. 2 is a plan view of the same, except that the work support is shown in broken lines only;

Fig. 3 is a vertical sectional view on the line 3—3 of Fig. 2; 60

Fig. 4 is a bottom plan view of the presser foot;

Fig. 5 is a sectional view on the line 5—5 of Fig. 3; and with the yielding portions of the presser foot at their lower limit of movement; 65

Fig. 6 is a similar view but showing the yielding sections at their upper limit of movement;

Fig. 7 is a front view of the presser foot; 70

Fig. 8 is a sectional view of the presser foot on the line 8—8 of Fig. 2;

Fig. 9 is a longitudinal sectional view longitudinally through the presser foot;

Fig. 10 is a perspective view of the portion of the presser foot which is rigidly secured to the supporting shank; 75

Fig. 11 is a perspective view of one of the yielding sections, and

Fig. 12 is a plan view of the throat plate 80 and the fabric engaging portions of the feed dog.

My improved presser foot as above noted, is particularly adapted for a machine making a flat covered seam, that is, for joining two fabric sections while the edges thereof are flat and unfolded by cross connected lines of stitching, which not only join the fabric sections, but cover the raw edges thereof. The fabric sections are preferably 85 slightly overlapped and are joined by a three-needle stitch covering mechanism, wherein the center needle passes through the overlapped fabric sections while the outer needles pass outside of the respective edges 90 of the fabric sections so that the looper 95

thread on one face of the fabric sections and the cross thread on the other face of the fabric sections joining the needle thread loops will cover the edges of the fabric sections.

The presser foot is provided with a slot leading into the front end thereof which is in line with the hole through which the needles pass and communicates therewith. This 10 slot guides the upturned edges of the fabric sections so that they may be trimmed, and the trimmed edges through the shaping of the walls of the slot are caused to overlap one upon the other and are thus directed to 15 the stitching mechanism.

The presser foot consists of a main section rigidly carried by a supporting shank. This main section in the line of the needles is disposed substantially in rear of the 20 needles. Said main section extends to one side and then forwardly from this portion in rear of the needles and is provided with a groove or recess in which is located the yielding section of the foot. This yielding 25 section extends alongside of and in front of the needles. On the other side of the section in rear of the needles there is a yielding section which extends alongside of and in front of the needles. The two yielding sections have their adjacent edges spaced and shaped so as to receive the upturned edges of fabric sections, direct the same to a trimming mechanism, and then turn said trimmed edges down into overlapped relation. The spring which causes 30 one of the yielding sections to move downwardly against the fabric is so constructed and arranged that the tension of the spring may be readily varied and thus the pressure 40 of the yielding section on the fabric varied. The stationary member of the trimming mechanism is mounted on the main section of the presser foot and on that portion thereof which projects forwardly and is recessed for the yielding member referred to 45 above.

Referring more in detail to the drawings, I have shown my improved presser foot as applied to a feed-off-the-arm type of machine. Said machine includes a work supporting arm 1 which is provided with a throat plate 2 at its forward end. Feed dogs 3 and 4 are provided with fabric engaging sections working in suitable slots 50 in the throat plate as indicated in Fig. 12 of the drawings. The throat plate is provided with a needle hole 5 and stitch fingers 6. The needles are indicated at 7, 8 and 9 in Fig. 2 of the drawings, and are three 55 in number. These needles are carried by a suitable needle bar 10. The material is fed off from the end of the arm by these feed dogs 3 and 4. Cooperating with the needles 7, 8 and 9 beneath the work support 60 is a looper 11 carried by the looper shaft 12.

This looper lays a looper thread into all of the needle loops which connects the needle loops and also covers the edge of the under fabric sections. The needle threads are joined on the upper face of 70 the fabric by a cross thread laid by a suitable cross thread laying mechanism not shown in the drawings.

Cooperating with the feed dogs is a presser foot which includes a main section 75 13, a yielding section 14, and a yielding section 15. The main section 13 is rigidly carried by the supporting shank 16 which in turn is attached to the presser supporting bars 17. This main section 13 comprises 80 a foot section 18 which is cut away at 19. This foot section 18 is directly in rear of the needles and is substantially wholly in rear of the needles. Said section is substantially the same width as the covered seam. Said seam 85 after it is completed, passes into the cut away portion 19 and then underneath the foot section 18. The main section 13 of the foot is also provided with a fabric engaging section 20 which extends forwardly and serves as a support for the stationary member 90 of the trimming mechanism. Said stationary member is indicated in dotted lines at 21 in Fig. 2. Cooperating with this stationary member of the trimming mechanism is a movable member 22 carried by an arm 23. The foot section 20 is recessed at 24 to receive the stationary member of the trimming mechanism, and said member is held in place by a clamping plate 25 100 secured to the foot section 20 by screws 26, 26.

The main section 13 is provided with a recess or groove 27 which extends the full length of the presser foot and located in 105 said groove or recess 27 is the yielding section 14. Said yielding fabric engaging section 14 is provided with an upwardly extending shank 28 which slides in a recess provided therefor in the main section 13 of the foot. A spring 29 is located 110 in a recess 30 in said shank 28 and bears against the lower end of said recess. The upper end of this spring 29 bears against a collar which can be shifted up and down by means of the screw 31. By turning this screw 31, the tension of the spring 29 may be varied. A stop screw 32 is threaded into the main section of the foot 13 and the inner 115 end of said stop screw extends into a slot 33 in the side of the shank 28. This slot is of sufficient length to allow fabric engaging section 14 to move vertically, but the upper end of the slot engages a screw 120 and limits the downward movement of said yielding section when the entire foot is 125 lifted off from the fabric.

Said yielding section 14 is provided with an opening 34 in which is located a second auxiliary section 35 carried by an arm 36 130

pivoted at 37 to the fabric engaging section 20 of the presser foot and yieldingly pressed downwardly by means of a spring 38.

Said yielding section 14 also carries an arm 39 which is provided with spaced stitch fingers or upper thread guides 40. These extend between the needles and a cross thread is laid over these fingers and is fed off from the same by the feed of the machine. These fingers together with the stitch fingers on the throat plate aid in the chaining off between articles, and also in the formation of the covering stitches.

On the opposite side of the foot section 18 from the yielding section 14 is located the yielding section 15. Said yielding section 15 is provided with a shank 41 which slides between the guiding walls 42, 43 carried by the main section of the presser foot. The cover plate 44 holds the shank in place, and a spring 45 yieldingly forces said section 15 downwardly. A stop screw 48 passing through the opening in the shank limits the downward movement of the yielding section 15 when the presser foot is raised. The inner face of the fabric engaging section 14 is beveled at 47 and curved at 46 so as to cooperate with the curved surface 49 on the yielding section 15. These curved and beveled surfaces are so shaped as to receive the upturned edges of the fabric sections and direct the same to the trimming mechanism and after they are trimmed, turn down said trimmed edges into overlapped relation to each other. It will be noted that the two sections are yieldingly mounted so that they are capable of independent upward movement. This is of great advantage in guiding the edges of the fabric sections and controlling the same, and at the same time to permit cross seams in the fabric sections to readily pass through the foot.

By my improved construction of presser foot, the fabric is firmly held in engagement with the fabric engaging sections of the feed dog, both in rear of the needles and at the side of the needles. The foot is raised by the thickness of the seam, and when so raised, the yielding sections move downwardly as indicated in Fig. 5, so as to firmly hold the fabric sections of single thickness at each side of the needle in cooperative relation to the feed dogs. It will be noted that the fabric sections until they reach the needles, are independently fed by the feed dogs. The means for adjusting the tension on one of the yielding sections enables the pressure on the fabric sections to be independently varied and thus the two fabric sections caused to be fed evenly. The main section of the presser foot which is rigidly carried by the supporting shank, engages the fabric sections after they are stitched, and the seam is formed, and therefore, the greatest pressure of the presser foot

against the feed dogs, is brought to bear directly upon the finished seam. This also tends to a very uniform feeding of the fabric sections being stitched.

It is obvious that minor changes in the details of construction may be made without departing from the spirit of the invention as set forth in the appended claims.

Having thus described the invention, what I claim as new and desire to secure by Letters Patent, is:—

1. The combination with a stitch forming mechanism, for forming covering stitches including a plurality of needles; of a feed dog and a presser foot, said presser foot including a supporting shank, a main section rigidly carried thereby and engaging the fabric sections in rear of the needles, and yielding fabric engaging sections located respectively at the sides of and in front of said needles, said yielding sections having inclined spaced overlapping parts in front of the needles arranged so as to guide and overlap the edge portions of the fabric sections.

2. The combination with a stitch forming mechanism for forming covering stitches including a plurality of needles; of a feed dog and a presser foot, said presser foot including a supporting shank, a main section rigidly carried thereby and engaging the fabric sections in rear of the needles, and yielding fabric engaging sections located respectively at the sides of and in front of said needles, said yielding sections being spaced and shaped in front of the needles so as to guide and overlap the edge portions of fabric sections, and means for varying the pressure of one of said yielding sections relative to the other.

3. The combination with a stitch forming mechanism for forming covering stitches including a plurality of needles; of a feed dog and a presser foot, said presser foot including a supporting shank, a main section rigidly carried thereby and engaging the fabric sections in rear of the needles, yielding fabric engaging sections located respectively at the sides of and in front of said needles, said yielding sections being spaced and shaped in front of the needles so as to guide and overlap the edge portions of fabric sections, and stitch fingers carried by one of said yielding sections and extending between the needles.

4. The combination with a stitch forming mechanism for forming covering stitches including a plurality of needles; a feed dog and a presser foot, said presser foot including a supporting shank, a main section rigidly carried thereby and located substantially in rear of the needles, said main section having a portion extending laterally and forwardly alongside of the needles, said main section having a recess extending

longitudinally thereof, and a yielding fabric engaging section located in said recess and extending alongside of and in front of the needles, a second yielding fabric engaging section located on the other side of the section in rear of the needles and extending alongside of and in front of the needles, said yielding sections being spaced from each other and shaped so as to guide and overlap the edge portions of fabric sections.

5. The combination with a stitch forming mechanism for forming covering stitches including a plurality of needles; a feed dog and a presser foot, said presser foot including a supporting shank, a main section rigidly carried thereby and located substantially in rear of the needles, said main section having a portion extending laterally and forwardly alongside of the needles, said main section having a recess extending longitudinally thereof, a yielding fabric engaging section located in said recess and extending alongside of and in front of the needles, a second yielding fabric engaging section located on the other side of the section in rear of the needles and extending alongside of and in front of the needles, said yielding sections being spaced from each other and shaped so as to guide and overlap the edge portions of fabric sections, said forwardly projecting portion of the main foot section being adapted to support the fixed member of the trimming mechanism.

30 6. The combination with a stitch forming mechanism for forming covering stitches including a plurality of needles, a feed dog and a presser foot, said presser foot including a supporting shank, a main section rigidly carried thereby and located substantially in rear of the needles, said main section having a portion extending laterally and forwardly alongside of the needles, said main section having a recess extending longitudinally thereof, a yielding fabric engaging section located in said recess and extending alongside of and in front of the needles, a second yielding fabric engaging section located on the other side of the section in rear of the needles and extending alongside of and in front of the needles, said yielding sections being spaced from each other and shaped so as to guide and overlap the edge portions of fabric sections, a spring for yieldingly forcing the section located in said recess downwardly, and means for varying the tension of said spring.

35 varying the tension of said spring, and stitch fingers carried by one of said yielding sections, said portion of the main foot section in rear of the needles being cut away to receive said stitch fingers.

7. The combination with a stitch forming mechanism for forming covering stitches including a plurality of needles; a feed dog and a presser foot, said presser foot including a supporting shank, a main section rigidly carried thereby and located substantially in rear of the needles, said main section having a portion extending laterally and forwardly alongside of the needles, said main section having a recess extending longitudinally thereof, a yielding fabric engaging section located in said recess and extending alongside of and in front of the needles, a second yielding fabric engaging section located on the other side of the section in rear of the needles and extending alongside of and in front of the needles, said yielding sections being spaced from each other and shaped so as to guide and overlap the edge portions of fabric sections, said forwardly projecting portion of the main foot section being adapted to support the fixed member of the trimming mechanism.

8. The combination with a stitch forming mechanism for forming covering stitches including a plurality of needles, a feed dog and a presser foot, said presser foot including a supporting shank, a main section rigidly carried thereby and located substantially in rear of the needles, said main section having a portion extending laterally and forwardly alongside of the needles, said main section having a recess extending longitudinally thereof, and a yielding fabric engaging section located in said recess and extending alongside of and in front of the needles, a second yielding fabric engaging section located on the other side of the section in rear of the needles and extending alongside of and in front of the needles, said yielding sections being spaced from each other and shaped so as to guide and overlap the edge portions of fabric sections, said yielding fabric engaging section located in said recess having an opening formed therethrough, and a second auxiliary yielding fabric engaging section extending through said opening and carried by the rigid foot section.

In testimony whereof, I affix my signature.
JAMES R. MOFFATT.
